(57) CLAIM

The ornamental design for a frozen dessert holder, as shown and described.

DESCRIPTION

FIG. 1 is a perspective view of a frozen dessert holder showing my new design;

FIG. 2 is a top plan view thereof;

FIG. 3 is a side elevational view thereof; and,

FIG. 4 is a bottom plan view thereof.

The broken lines are included for the purpose of illustrating environment and form no part of the claimed design.
